Primary Examiner—Jeffrey Asch*Attorney, Agent, or Firm*—Mueting, Raasch, Gebhardt & Schwappach, P.A.[57] **CLAIM**

The ornamental design for compact wireless telephone, as shown and described.

DESCRIPTION

FIG. 1 is a front perspective view of the compact wireless telephone with an outboard battery pod, an earpiece, and a wrist band in phantom showing our new design;

FIG. 2 is a rear perspective view of the compact wireless telephone with an outboard battery pod, an earpiece, and a wrist band in phantom;

FIG. 3 is a top plan view;

FIG. 4 is a front elevation view;

FIG. 5 is a side elevation view showing the right side;
FIG. 6 is a rear elevation view;
FIG. 7 is a side elevation view showing the left side; and,
FIG. 8 is a bottom plan view.

The broken line showings of FIGS. 1 and 2 are for illustrative purposes only and form no part of the claimed design.
